[57] CLAIM

The ornamental design for a brace for stabilizer of V-tail aircraft, as shown and described.

DESCRIPTION

FIG. 1 is a front perspective view of a brace for stabilizer of V-tail aircraft, showing our new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a side elevational view thereof; and

FIG. 7 is a side elevational view of the side opposite that shown in FIG. 6 thereof.

FIG. 1.

FIG. 2.

FIG. 3.

FIG. 4.

FIG. 5.

FIG. 6.

FIG. 7.
